Original application August 23, 1941, Serial No.
408,015. Divided and this application August
25, 1944, Serial No. 551,100

5 Claims. (Cl. 68—262)

1

The invention relates to wringers of the type used in connection with household laundry machines comprising wringer rolls, and has particular reference to new and improved means for adjustably varying the spring pressure exerted on the rolls.

One of the objects of the invention is to provide a wringer structure embodying novel roll tensioning means which is sturdy in construction and readily and accurately adjustable, and which is self-acting to maintain yieldably any preselected adjustment.

Another object is to provide a new and improved adjustable spring tensioning means which comprises an adjustable abutment member, and an intermediate detent member in yieldable latched engagement with the abutment member and adapted for engagement with the spring for the wringer rolls, and which is mounted on a separable head section of the wringer frame and separable as a unit from the spring.

Further objects and advantages will become apparent as the description proceeds.

In the accompanying drawings,

Figure 1 is a longitudinal vertical section taken along line 1—1 of Fig. 3 of a wringer having a roll tensioning means embodying the features of my invention.

Fig. 2 is a fragmentary plan view showing details of the roll pressure adjusting means as seen from the inside of the head looking in the direction indicated by the arrows 2—2 of Fig. 1.

Fig. 3 is a transverse sectional view, on an enlarged scale, through the wringer structure, and taken substantially along the irregular line 3—3 of Fig. 1.

Fig. 4 is a fragmentary perspective view, on an enlarged scale, showing details of the latch and manipulating means for the wringer head.

In general, the exemplary form of wringer structure illustrated herein embodies a frame comprised of a fixed section or base 20 (Fig. 1) supporting spaced upstanding end members in the nature of concealing walls or shrouds 21 and 22 arranged for cooperation with a movable section or head 23. The base 20 carries a pair of upstanding, channel-shaped side stiles 24 and 25, located within and concealed by the walls 21, 22. A pair of cooperating wringer rolls 26 and 27 extend between the side stiles 24 and 25 and are supported from the side stiles by half bearings 28 and 29 for the shaft 30 of the lower wringer roll 26 and by slidable bearing blocks 32 and 33 for the shaft 34 of the upper roll 27. The end wall of the left-hand side stile 25 is slotted, as at 31,

2

to permit the left end of the shaft 30 to extend therethrough for connection with the roll driving mechanism. Rigid with the blocks 32 and 33 are carrying plates 35 and 36 which extend above and beyond the upper roll and the bearing blocks and receive, through slots 38 and 39, the respective ends of a leaf spring 37 located in the head above the upper roll 27. Upon application of pressure to the central portion of the leaf spring 37 by a tensioning device (indicated generally at 40) carried by the head, operative roll pressure is established. The present invention relates primarily to the tensioning device 40 which is readily and conveniently adjustable to vary the roll pressure.

The head 23 is a generally channel-shaped member closed at its ends and longitudinally dimensioned to extend between and telescope over the end walls 21 and 22. Each of the end walls is slightly inwardly offset at its top edge (as seen at 41) to receive the head section and hold it in vertical alinement with the end walls when the parts are established in operative relation. The end walls are smoothly rounded and the head has an arcuate contour completing the curve of the assembly. The left-hand end wall 22 which houses the side stile 25 is enlarged longitudinally to form a gear box enclosing the reversing gearing, generally indicated at 42.

In the present structure the wringer drive mechanism, as shown in Fig. 1, comprises a drive shaft 50, rotatably housed in a sleeve 51 supported to depend from a boss 52 on a box frame 53 bolted or otherwise secured within the end member 22. These parts form the support by which the wringer is mounted on the washing machine. Power to drive the wringer is transmitted to the shaft 50 by a suitable wringer drive shaft (not shown). The shaft 50 extends axially upwardly through the box frame 53 and is journaled at its upper end, as at 54, in the frame. The reversing gearing mechanism embodies a unitary arrangement of a pair of spaced gears 55 and 56 connected by an intermediate clutch shifting member or collar 57. This unit is slidably splined on the shaft 50 for rotation therewith. The extended end of the lower wringer roll shaft 30 in the end member 22 is connected through a universal coupling 58 with a crown gear 59 which is journaled, as at 60, on the box frame 53 for selective engagement by the gears 55 and 56.

Means is provided for shifting the unitary gear assembly along the shaft 50 from a central, neutral position to effect selective engagement of the gear 55 or 56 with the crown gear 59 to drive

the rolls in one direction or the other. To this end, a bearing member 61 supports a horizontal actuator shaft 62 that extends longitudinally beyond the end member and has an operating handle 63 thereon. The inner end of the shaft 62 has a radial crank plate 64 centrally fixed thereto. A shifting link 65 is pivotally connected as at 64^a (Fig. 3) to one arm of the plate 64 eccentrically of the shaft 62 and extends generally upwardly for pivotal connection, as at 66^a, with a slide 66 mounted on the box frame 53 for vertical movement. The slide carries a stud 67 adapted to engage in an annular groove 68 formed in the clutch member 57 (Fig. 1). The link 65 has an S-shaped form to insure that when the shaft 62 is rotated by the hand lever 63 (for instance in a clockwise direction, looking at Fig. 3) the upward swing of the crank plate arm will act through the link 65 to shift the slide 66 upwardly and move the gear 55 into driving engagement with the gear 59. Opposite movement of the hand lever 63 produces a downward movement of the linkage to effect engagement between the gears 56 and 59. A spring pressed detent 71 impositively latches the slide 66 in its three positions (forward, neutral and reverse) by engagement in appropriately positioned notches formed therein.

In the present wringer the head section is supported for movement into and out of operative association with the base section and the structure includes means for latching the frame sections together, for applying operative pressure to the wringer rolls when the frame sections are so related and for quickly unlatching the frame sections to permit separating movement thereof, accompanied by release of the pressure from the rolls. Means is provided for separately latching the opposite ends of the head section to the base section, together with means acting to successively shift the head longitudinally or in the direction of its length to engage the latching means at one end of the frame and thereafter to draw the head section toward the base section to establish a latched engagement therebetween at the other end of the frame. At the same time the rolls are placed under operative pressure. These movements may be conveniently produced by the manipulable member for controlling the reversing gearing, the preferred arrangement including means permitting independent manipulation of the reversing gearing once the operating condition of the frame has been established.

In the embodiment illustrated, the cooperating latching means for one end of the head and frame sections is a simple interfitting engagement between the parts, such as an internal tongue or projection 75 on the right hand end of the head (Fig. 1) and an aperture 76 in the end member 21, these parts being engageable or disengageable upon longitudinal shifting movement of the head in one direction or the other.

For supporting and guiding the head in its longitudinal movements, a pair of brackets 77 are rigidly secured on opposite sides of the other or left end of the head (see Figs. 3 and 4) and are inwardly offset, as indicated at 78, to depend into the end member 22. These brackets 77 are formed with generally vertically extending slots 79 which slidably receive the end portions of a pin 80 rigid with and extending transversely of the frame 53. The lower portions 81 of the slots 79 extend at an angle to the vertical or downwardly and to the left (Figs. 1 and 4). The an-

5 gular relationship is such that when the head is in its raised inoperative position, with the pin 80 extending through the lower ends of the angular slot portions 81, downward movement of the brackets 77 with the head will first cam the head longitudinally to the left to engage the interfitting parts 75, 76 at the right-hand end of the frame. Thereafter, the pin traverses the vertical portions of the slot 79 to guide the head to a seated position on the end member 22 and engage the latch means at the left-hand end of the frame, as shown in Fig. 4.

In the present instance, such movement of the head 23 into operative association with the end members 21 and 22 is effected by manipulation of the gear shift lever 63 from its neutral position, as shown in Fig. 1, to drive the rolls in either direction. To this end, the crank plate 64 carries a pair of spaced antifriction rollers 82 and 83 mounted in eccentric relation to the shaft 62. These rollers are selectively moved to engage cam surfaces 84 and 85, respectively, of an actuator 86 when the shaft is rotated in one direction or the other. As seen in Fig. 3, the shifting link 65 is generally S-shaped to provide clearance recesses 69, 70 for the rollers 82 and 83, respectively. The actuator 86 is generally U-shaped to straddle the wringer post 52, and is pivotally supported at its inner ends, as by a pivot pin 87, on a bracket 88, which is rigidly secured, as at 89 (Fig. 1), to the bottom of the end member 22.

35 A pair of upwardly extending links 101 are pivoted, as at 100, to the opposite sides of the actuator 86 and each of these links is pivotally connected at its upper end to a short link 102. The short links in turn are pivotally supported by a pin 103 rigidly carried by ears 104 formed as 40 extensions of the brackets 77 on the head 23. By this arrangement, actuation of the handle 63 from its central inoperative position to drive the rolls in either direction will cause one of the rollers 82, 83 to depress the actuator 86 which, through the linkage 100, 101, 102, 103 and 104 45 will draw the head downwardly toward and into its seated relation with the base. A pair of tension springs 105 having their respective ends secured to the actuator 86 and to pins 53^a (Fig. 3) fixed on end member 22 pull upwardly on the actuator and through the connecting linkage 50 exert a force tending to hold the head in its raised and somewhat longitudinally displaced inoperative position.

55 The latch mechanism, employed for holding the left end of the head in its depressed, operative position, is automatically engageable as an incident to this downward movement of the head to its operative position and is releasable in an emergency by a simple quick release mechanism. At the same time, the reversing gear mechanism is returned to its neutral position as the actuator 86 is raised by the linkage 101, 102 and strikes one or the other of the rollers 82, 83 (if not in their neutral position) to return the mechanism to neutral. The instant latch mechanism includes a latch plate 106 pivotally supported on the wringer frame, as by the horizontal pin 80, to project generally upwardly therefrom, as shown best in Fig. 4. A latching member in the form of a horizontal pin 107 is rigidly secured in the head to extend generally parallel to the pin 80 and is adapted, upon depression of the head, for latching engagement in complementary notches 108 formed in side flanges 109 of the 60 latch plate 106. As shown in Figs. 1 and 4, the 70 75 latch plate 106.

margins of the notches 103 that engage the pin 107 to hold the head are formed at a slight angle so that the engagement is impositive and not self-sustaining. Above these angular margins the flanges 109 are formed with inclined cam surfaces 110 (Fig. 4) upon which the pin 107 rides to retract the latch plate for engagement with the pin 107. A spring 111, having one end secured in the frame 53 and the other on the plate 106 is of sufficient strength to cause the latch plate 106 to snap into latching engagement with the pin 107 when the head has been depressed to its operative position, but is of insufficient strength per se to maintain the latching engagement. A holding member 112 for the latch plate is pivotally supported on the pin 103 to extend over and past the upper end of the latch plate 106, and has an intermediate shoulder 113 for engagement with the upper end of the latch plate 106 when the latter is engaged with the pin 107. To maintain the operative relationship of the parts, a spring 114, having one end anchored in the end member 22 and the other end secured to the holding member 112, yieldably urges the latter into engagement with the latching plate 106.

The parts are maintained in this operative relation until the holding member 112 is released. This mechanism is arranged for convenient actuation from either side of the wringer head by the user in an emergency. Thus, each side of the wringer head supports a release or impact bar 120 (Fig. 3) projecting outwardly therefrom immediately above the upper roll. The release bars are mounted for swinging movement relative to the head by such means as pivot pins 121 supported by ears 122 inside the head engaging arms 123 on the release bars (Figs. 3 and 4). The arms 123 at the end of the head adjoining the holding member 112 have horizontal continuations adapted to underlie and bear against an extended finger 124 on the holding member 112.

Hence, when the holding member is in operative engagement with the latch plate 106, inward movement of either release bar will release this end of the head, and the upward movement thereof is followed by a release of the latching means at the other end as the pin 80 rides through the angular portions 81 of the slots 79.

The tensioning device 49 (Figs. 1, 2 and 3) is carried by the head 23 for cooperation with the central portion of the spring 37 to place the rolls 26 and 27 under operative spring pressure. In the present instance, this device comprises an element 125 in the form of a generally U-shaped detent lever having legs pivotally supported by ears 126 depending from opposite sides of a bracket 126^a rigid with the head. The element 125 is designed to bear against and stress the spring 37 when the head is latched to the frame.

For adjusting or varying the stressing effect of the element 125 on the spring 37, a longitudinally shiftable stepped plate or bar 127 is mounted to slide through apertures in longitudinally spaced depending lugs 128 on the bracket 126^a. The steps on the plate 127 are defined by longitudinally spaced recesses located at varying distances from the upper wall of the head and adapted for selective engagement with the upper edge of the detent element 125, the lower edge of the latter bearing against the spring 37. A hand actuator 129 is rigid with a plate 127, and projects outwardly therefrom through a slot 130 in the head for convenient manipulation.

Suitable means is provided for maintaining the detent element 125 yieldably in engagement with

any one of the recesses in the stepped plate 127. In the present instance, this means comprises a flat leaf spring 131 rigid with one arm of the element 125 and bearing at its free end normally under a flexed condition against the underside of the head 23.

In operation, as the shaft 62 is rotated to depress the head 23 and engage the wringer rolls 26 and 27, the pin 80, through the agency of the angular portions 81 of the slots 79, cams the head longitudinally to engage the latch members 75 and 76. Further rotation of the shaft 62 depresses the head 23, tensioning the spring 37 and, at the same time, effecting engagement of the latch plate 106 with the pin 107 and the shoulder 113 with the plate 106. To release the rolls from operative pressure engagement, the impact bars 120 are actuated to raise the trigger 124.

The tension imposed on the wringer rolls 26 and 27 by the spring 37 may be selectively adjusted by shifting the stepped plate 127 longitudinally to locate the intermediate portion of the spring at different distances from the top wall of the head 23. Such adjustment of the plate 127 may be easily and quickly effected by means of the hand actuator 129. The spring 131 serves to maintain the plate 127 yieldably in any position of selected adjustment when the head 23 is released from the main frame of the wringer.

The present application is a division of my co-pending application Serial No. 408,015, filed August 23, 1941, Patent No. 2,360,369, issued October 17, 1944.

I claim as my invention:

1. In a wringer, the combination of a frame, including a fixed section and a separable head section mounted for movement into and out of operative engagement with respect to said fixed section, wringer rolls journaled in said frame, a spring for placing said rolls under operative pressure, and means carried by said head section for tensioning said spring upon movement of said head section into operative engagement with said fixed section, said means including a member pivotally mounted on the underside of said head section and projecting therefrom for engaging said spring upon operative association of said head section with said fixed section, a stepped plate slidably mounted between said head section and said member for selective manipulation to shift said member toward and away from said spring whereby to vary the stressing effect thereof on said spring in accordance with the position of said stepped plate.

2. In a wringer, in combination with a frame including a fixed section and a separable head section mounted for movement into and out of operative engagement with said fixed section, wringer rolls journaled in said frame and a spring for placing said rolls under operative pressure when said head section is engaged, tension adjusting means for said spring including a detent member movably mounted on said head section and adapted to impart pressure to said spring,

60 a stepped member adjustably mounted on said head section and formed with a series of stepped surfaces selectively engageable with said first mentioned member to vary the spacing of the latter from said fixed section, and spring means for urging said first mentioned member yieldably into engagement with said stepped member whereby to maintain the latter in selected position of adjustment.

65 3. In a wringer, the combination of a frame including a fixed section and a separable head

70 75

section mounted for movement into and out of operative engagement with said fixed section, vertically spaced parallel wringer rolls journaled in said frame, the upper roll being supported for vertical movement, a bow spring acting at opposite ends to urge said upper roll against said lower roll, a bracket secured to the underside of said head section, said head section and bracket being formed with a longitudinal slot, a stepped plate slidably guided in said bracket for longitudinal adjustment, and being formed along its lower edge with a longitudinal series of recesses of progressively increasing distances from said head section, a hand actuator rigid with said stepped plate and projecting upwardly through said slot, and a detent lever engageable selectively in said recesses and against the central portion of said spring to vary the spacing of said spring from said head section.

4. In a wringer, the combination of a frame including a fixed section and a separable head section mounted for movement into and out of operative engagement with said fixed section, vertically spaced parallel wringer rolls journaled in said frame, the upper roll being supported at opposite ends in bearing blocks vertically slid-able in said frame, a bow spring engaging said blocks to urge said upper roll against said lower roll, a bracket secured to the underside of said head section and having laterally spaced depending ears at one end and longitudinally spaced depending guide lugs, said head section and bracket being formed with a longitudinal slot, a stepped plate slidably guided in said lugs against the underside of said bracket for longitudinal ad-justment, and being formed along its lower edge with a longitudinal series of recesses of progres-sively increasing distances from said head sec-tion, a hand actuator rigid with said stepped plate and projecting upwardly through said slot, and a U-shaped detent lever having legs pivoted to said ears and having a cross member engageable at the upper edge selectively in said recesses and the lower edge against the central portion of said

5

spring to vary the spacing of said spring from said head section.

5. In a wringer, the combination of a frame including a fixed section and a separable head section mounted for movement into and out of operative engagement with said fixed section, vertically spaced parallel wringer rolls journaled in said frame, the upper roll being supported at opposite ends in bearing blocks vertically slidable in said frame, apertured plates secured to and extending upwardly from said blocks, a bow spring extending at opposite ends through said plates and engaging said blocks to urge said upper roll against said lower roll, a bracket secured to the underside of said head section and having laterally spaced depending ears at one end and longitudinally spaced depending guide lugs, said head section and bracket being formed with a longitudinal slot, a stepped plate slidably guided in said lugs against the underside of said bracket for longitudinal adjustment, and being formed along its lower edge with a longitudinal series of recesses of progressively increasing distances from said head section, a hand actuator rigid with said stepped plate and projecting upwardly through said slot, a U-shaped detent lever having legs pivoted to said ears and having a cross member engageable at the upper edge selectively in said recesses and the lower edge against the central portion of said spring to vary the spacing of said spring from said head section, and a leaf spring connected to said lever and engaging the interior of said head section to urge said lever yieldably against said stepped plate.
